UNITED STATES PATENT OFFICE

CHRISTIAN CHRISTIANSEN, OF SWAMPSOFT, MASSACHUSETTS, ASSIGNOR TO ROTARY MACHINE COMPANY, OF LYNN, MASSACHUSETTS, A CORPORATION OF MASSACHUSETTS

WORK FEED MECHANISM

Application filed July 11, 1930. Serial No. 467,324.

This invention relates to mechanism for feeding work and is particularly adapted for use with machines for applying adhesive tape to the side portions of shoe uppers and similar machines.

It has been common practice heretofore to provide in machines of this type a work feed mechanism including positively driven upper and lower feed rolls between which the work is moved. In handling work in machines of this type it is often necessary to turn the work as it is being fed through the machine, particularly when applying tape to the edges of the side portions of shoe uppers. Not only has this been difficult to accomplish but often has caused the formation of wrinkles on the work.

It is an object of the present invention to overcome these difficulties and provide work feed mechanism adaptable for machines of this general type which facilitates turning of the work as it passes through the machine.

In accordance with the invention, I provide a work feed mechanism which avoids simply posing a constant pressure upon the work, as is the case with cooperating work feed rolls, and which utilizes a single feed roll with which cooperates a plurality of work feed feet which are moved successively to engage and feed the work between the same and the roll.

The invention will be more clearly understood from the following description in conjunction with the accompanying drawings; in which,

Fig. 1 is a front elevational view of a machine embodying the invention;

Fig. 2 is a side elevational view of the machine;

Fig. 3 is a side elevational view of the same partly in section, taken at the opposite side of the machine with part of the casing removed to show the operating mechanism.

Fig. 4 is an enlarged side elevational view, partly in section, of a portion of the machine with the work feed mechanism in operative position.

Fig. 5 is a similar view with the work feed mechanism in inoperative position.

Figs. 6, 7 and 8 are detailed sectional views

showing the relationship of the various parts of the feed mechanism at different periods during its cycle of operation.

Fig. 9 is a sectional elevational view taken upon the line 9—9 of Fig. 2; and

Fig. 10 is a plan view of a specimen of work such as a shoe upper having adhesive tape applied to its edges by the machine illustrated.

Before explaining in detail the present invention, it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention beyond the terms of the several claims hereto appended as considered in view of the prior art and the requirements thereof.

The machine illustrated in the drawings comprises a base 10 upon which a frame 11 is secured in any suitable manner, as by screws 12. This frame is chambered to provide a casing adapted to be closed by a cover plate (not shown) and is provided with upper and lower forwardly extending arms 11a and 11b. Shafts 13 and 14 are mounted for rotation in suitable bearings in the frame 11 and also in hubs (not shown) formed as a part of a bracket plate 20. An upper feed roll 15 is mounted upon the outer end of the shaft 14 for rotation therewith. A gear 16 is fixed in any suitable manner to a hub (not shown) secured upon the shaft 14. The bracket 20 is also provided with a hub 25 within which is journaled a drive shaft 26. The shaft 26 has a pinion 27 fixed upon its inner end and a wheel 28 fixed upon its opposite end and connected with a suitable source of power as by a belt 23. The bracket 20 also has a hub (not shown) within which is journaled a stud shaft 35, the latter carrying a gear 37 meshing with the pinion 27 carried by the shaft 26. A pinion 38 is also mounted upon the shaft 35 and meshes with 100

a large gear 42 secured to the shaft 13. The gear 42 is at all times in mesh with the gear 16 of similar diameter, carried by the upper shaft 14.

5 Mounted within the frame arm 11b is a rock shaft 44. Upon the rear end of this rock shaft is mounted a collar 45a of a depending arm 45 held upon the shaft, as by set screws 46 engaging a slabbed off portion 44a of the rock shaft.

10 An arm 50 is secured to the front end of the shaft 44 and is inwardly offset at its free end to form a crank provided with a hub 51. Connected to the shaft 13 by a universal 15 connection 13a is a shaft 52 mounted in bearings in the hub 51. A casing 53 having spaced parallel walls 54 and 55 surrounds the outer end of the shaft 52 and is suitably clamped upon the hub 51. For this purpose, the lower 20 end of the wall 55 is provided with a split bearing 56 which is clamped upon the hub 51, as by a screw 57. A plurality of movable members 58 and 59 are positioned between the walls 54 and 55 of the casing 53 and each 25 is provided at its outer end with a feed foot 60 adapted to engage work W and move it with the feed roll 15. Eccentrics 61 and 62 are adjacently mounted on the shaft 52 with their longest radii angularly disposed and 30 adapted to be received in bearings 63 and 64 near the inner ends of the members 58 and 59 respectively. Guide pins 65 and 66 rotatably carry the members 58 and 59 respectively and are provided with heads 67 and 68 35 adapted to be received in guide slots 70 and 71 in the walls 54 and 55. A work guide 72 is pivotally mounted near one end of the casing 53 on a pin 74 mounted in the wall 55 and is provided at its other end with a handle 75. The work guide 72 is held in its operative position by a spring 76, one end of 40 which engages a socket 77 in the guide 72 and the other end of which rests upon a shoulder 78 on the wall 55.

45 Mounted upon a fixed stud 80 is a lever 81, the free end of which is connected to a treadle rod 82 operated from a suitable floor treadle. The lever 81 is connected intermediate its ends to the arm 45 by a spring 83. The 50 lower part of the arm 45 is wedge-shaped and normally rests against a cam 81a formed on the inner face of the lever 81. When the lever 81 and the arm 45 are in normal positions, as shown in full lines in Fig. 3, the arm is 55 locked against movement by virtue of the abutting face of the cam 81a. Upon depressing the treadle rod 82, the lever 81 will be swung downwardly toward the dotted line position and the spring 83 will act to swing the arm 45 toward the dotted line position, the lower end of the arm travelling on the cam face 81a. Upon releasing the treadle the parts will return to the full line positions by the action of the spring, the upper edge of the 60 lever 81 engaging a stop shoulder 45b on the 65

face of the arm 45. When the arm 45 is swung in this manner it will rock the shaft 44, thereby rocking the crank arm 50, resulting in swinging the casing 53 out of operative position with respect to the feed roll 15.

70 A bracket 85 mounted upon the frame 11 is provided at its free end with a stud 86 upon which rotates a reel or holder 87a for tape 87 which is wound thereon. Rotation of the reel of tape 87 upon the stud 86 is resisted by a spring tension device 88 in the form of a spider having spring arms engaging the face of the tape holder or reel.

75 A bracket 90 is adjustably mounted upon the arm 11a adjacent the roll 15 and for this purpose is provided with a split bearing 91 which is clamped upon the arm 11a, as by screws 92. Shafts 93 and 94 are rotatably mounted in suitable bearings in the bracket 90 and are provided with paddle wheels 95, 96 respectively having radially extending blades 97. Suitable intermeshing gears 98, 99 are mounted upon the shafts 93, 94 respectively. A shaft 100 is also mounted for rotation in suitable bearings in the bracket 90 and is provided with a suitable gear 101 and a pinion 102 adapted to mesh respectively with the gear 98 and the gear 16. The paddle wheels 95, 96 are so arranged that the tape may pass therebetween with the plates 95 97 thereon alternately engaging and feeding relatively small spaced areas of the tape.

100 A tape guide is mounted in a slot 105 in the bracket 90 and comprises relatively adjustable members 106, 107 having offset fingers 108 and 109 depending therefrom. The member 107 is secured in fixed position within the slot 105 by a set screw 110 engaging a threaded opening in the bracket 90 and extending into the slot 105. An adjusting screw 111 is swivelled in an ear 112 upon one end of the member 107 and may be turned in order to space the guides different distances apart to accommodate different widths of tape.

110 When the machine is in operation, tape is fed from the reel 87a between the paddle blades 97 and is guided by the work guides 106, 107 on to the work W which passes between the roll 15 and the feed feet 60 which are brought successively into engagement with the work W to feed the same with the roll 15. The feed feet 60 on the ends of the members 58 and 59 are caused to move alternately into engagement with the work by the action 115 of the eccentrics 61 and 62 as the shaft 52 is rotated. As the shaft 52 rotates causing the eccentrics 61 and 62 to move the members 58 and 59, the latter are guided in a plane passing substantially through the eccentric carrying shaft 52 and the center of the roll 15 by engagement of the heads 67 and 68 in the guide slots 70 and 71. During this movement of the members 58 and 59 they are permitted to pivot about the pivot pins 65 and 66, thus 120 125 130

causing the eccentrics to move laterally with the rotation of the roll 15. It will be understood that while the feed feet 60 do not exert a constant pressure upon the work they bring about a substantially continuous step by step feed of the work and at the same time permit the work to be turned in any desired curved path.

I claim:

10 1. Work feed mechanism comprising a rotatable feed roll, a plurality of feed feet mounted for movement in a plane common to said roll, and means for actuating said feet successively to cause the same to cooperate with said roll to move work therebetween.

15 2. Work feed mechanism comprising a rotatable feed roll, a plurality of movable members each having a feed foot at one end, means for moving said members to cause said feet to move longitudinally and laterally in a plane common to said roll, said members operating successively to feed work between the same and said roll.

20 3. Work feed mechanism comprising a rotatable feed roll, a plurality of movable feed feet adapted for engagement with said roll, and means for moving said feet successively in an arcuate path to feed work between the same and said roll.

25 4. Work feed mechanism comprising a rotatable feed roll, a plurality of movable members each having a feed foot at one end, driving means operatively connected with each of said members to move said feet successively towards and away from said roll, and means for guiding said members to control their movement towards and away from said roll while permitting the same to pivot about a point located in a plane passing through said driving means and the center of said roll.

30 5. Work feed mechanism comprising a rotatable feed roll, a rotatable shaft, a plurality of eccentrics adjacently mounted on said shaft so that their longest radii are angularly disposed, a plurality of movable members each having a feed foot adapted for engagement with said roll, each of said members being provided with a bearing adapted to receive one of said eccentrics, and guide means for said members operative along a plane passing substantially through the center of said roll and said shaft while permitting said members to pivot about a point in said plane.

35 6. Work feed mechanism comprising a rotatable feed roll, a rotatable shaft, a plurality of eccentrics adjacently mounted on said shaft so that their longest radii are angularly disposed, a plurality of movable members separately actuated by said eccentrics and each having a feed foot at one end adapted for engagement with said roll, a guide pin rotatably mounting each of said members, and a separate guide for each of said pins

adapted to guide the same towards and away from said roll.

7. Work feed mechanism comprising a rotatable feed roll, a plurality of feed feet mounted for movement in a plane common to said roll, means for actuating said feet successively to cause the same to cooperate with said roll to move work therebetween, and means permitting said feet to be moved simultaneously towards and away from said roll.

8. Work feed mechanism comprising a rotatable feed roll, a support movable towards and away from said roll, a plurality of members movable with and relative to said support, each of said members having a feed foot at one end, driving means operatively connected with each of said members to move said feed successively relative to said support towards and away from said roll, and means for guiding said members to cause said feed to move towards, with and away from said roll when actuated by said driving means.

9. Work feed mechanism comprising a rotatable feed roll, a support movable towards and away from said roll, a plurality of members movable with and relative to said support, each of said members having a feed foot at one end, driving means operatively connected with each of said members to move said feet successively relative to said support towards and away from said roll, means for guiding said members to cause said feet to move towards, with and away from said roll when actuated by said driving means, and a work guide carried by said support.

In testimony whereof I affix my signature.
CHRISTIAN CHRISTIANSEN.
